(57) **CLAIM**

We claim the ornamental design for a one-cell beverage box,
as shown and described.

DESCRIPTION

FIG. 1 is a rear perspective view of one-cell beverage box
showing the claimed design with a top portion positioned in
an open configuration and a telescoping portion positioned
in a telescoped configuration.

FIG. 2 is a rear elevation view thereof.

FIG. 3 is a front elevation view thereof.

FIG. 4 is a right-side elevation view thereof.

FIG. 5 is a left-side elevation view thereof.

FIG. 6 is a top plan view thereof.

FIG. 7 is a bottom plan view thereof.

FIG. 8 is a plan view of the one-cell beverage box shown in
a fully collapsed configuration.

FIG. 9 is a front plan view of the one-cell beverage box
shown in a fully collapsed and flattened configuration; and,
FIG. 10 is a rear plan view of the one-cell beverage box
shown in the fully collapsed and flattened configuration.
Those features shown in broken lines, such as the broken
lines denoting lines of weakness shown in FIGS. 1–5 and
8–10, form no part of the claimed design.
